(57) **CLAIM**

The ornamental design for a beverage system, as shown and described.

DESCRIPTION

FIG. 1 is a front view of a beverage system showing our new design;

FIG. 2 is a left side view thereof;

FIG. 3 is a rear side thereof;

FIG. 4 is a right side view thereof;

FIG. 5 is a perspective view thereof;

FIG. 6 is a top view thereof;

FIG. 7 is a bottom view thereof;

FIG. 8 is a top view of the bottom covering portion shown in FIG. 1 with the container portion and the gasket portion removed for ease of illustration;

FIG. 9 is a bottom view thereof;

FIG. 10 is a front view thereof;

FIG. 11 is a left side view thereof;

FIG. 12 is a rear side thereof;

FIG. 13 is a right side view thereof;

FIG. 14 is a front view of the gasket portion shown in FIG. 1 with the container portion and the gasket portion removed for ease of illustration;

FIG. 15 is a left side view thereof;

FIG. 16 is a rear side thereof;

FIG. 17 is a right side view thereof;

FIG. 18 is a top view thereof;

FIG. 19 is a bottom view thereof;

FIG. 20 is a front view of the container portion shown in FIG. 1 with the gasket portion removed for ease of illustration;

FIG. 21 is a left side view thereof;

FIG. 22 is a rear side thereof;

FIG. 23 is a right side view thereof;

FIG. 24 is a top view thereof;

FIG. 25 is a bottom view thereof;

FIG. 26 is a front view of the container portion shown in FIG. 1 with the gasket portion and the bottom covering portion removed for ease of illustration;

FIG. 27 is a left side view thereof;

FIG. 28 is a rear side thereof;

FIG. 29 is a right side view thereof;

FIG. 30 is a top view thereof; and,

FIG. 31 is a bottom view thereof.
